(57) CLAIM

The ornamental design for a combined game board with set of game pieces as shown and described.

DESCRIPTION

1. Combined game board with set of game pieces
 1.1: Top, front perspective view of the combined game board with set of game pieces showing my new design in a position of use;

1.2: Front elevational view of the combined game board with set of game pieces with the game board and game pieces thereof shown separately for clarity of illustration;

1.3: Back elevational view thereof;

1.4: Right elevational view thereof;

1.5: Left elevational view thereof;

1.6: Top plan view thereof; and

1.7: Bottom plan view thereof.

The broken lines in the reproductions depict environmental structure of the combined game board with set of game pieces that forms no part of the claim.

1 Claim, 7 Drawing Sheets(56)
